FOREIGN PATENT DOCUMENTS

AU 349263 6/2013

Primary Examiner — Cynthia R Underwood*(74) Attorney, Agent, or Firm* — Christensen, Fonder, Dardi & Herbert PLLC(57) **CLAIM**

I claim the ornamental design for a tablet computer case, as shown and described.

DESCRIPTION

FIG. 1 is a perspective view of a tablet computer case; FIG. 2 is a detail view of the tablet computer case as depicted in FIG. 1;

FIG. 3 is another perspective view of the tablet computer case;

FIG. 4 is another detail view of the tablet computer case taken from encircled area labeled “4” on FIG. 1;

FIG. 5 is another detail view of the tablet computer case taken from encircled area labeled “5” on FIG. 1;

FIG. 6 is another detail view of the tablet computer case taken from encircled area labeled “6” on FIG. 1 shown slightly titled;

FIG. 7 is a view from below of the tablet computer case; and, FIG. 8 is a front view of the tablet computer case.

The figures include broken lines that are directed to environment and are for illustrative purposes only; the broken lines form no part of the claimed design.
